UNITED STATES PATENT OFFICE.

WILLIAM H. TOWERS, OF PHILADELPHIA, PENNSYLVANIA.

PENHOLDER.

Specification of Letters Patent No. 12,734, dated April 17, 1855.

To all whom it may concern:

Be it known that I, WILLIAM H. TOWERS, of the city and county of Philadelphia and State of Pennsylvania, have invented a new and useful Attachment to Penholders and Pens for Supplying the Latter with Ink as It is Exhausted Therefrom, which is described as follows, reference being had to the annexed drawings of the same, making part of this specification.

Figure 1 is a view of a pen holder and pen with the improvement attached. Fig. 2 is a side elevation of ditto. Fig. 3 is a section of ditto.

Where the same letters occur in the figures they refer to corresponding parts.

The nature of this invention and improvement consists in inserting in the lower hollow end of the pen holder, or attaching to any convenient part of this end of the same, a small lever made flat or curved at its lower end in order to receive between its surface and the lower concave part of the pen a small piece of sponge or other porous and elastic substance capable of absorbing and retaining the ink, and having a button at its upper end or otherwise formed at this part to enable the penman to depress the same to compress the sponge between the lower end of the lever and the pen, and cause the ink to be extracted therefrom, and keep up the supply of ink to the nibs as it is used in writing, at the will of the penman, without the constant dipping of the pen in the inkstand, as heretofore required.

To enable others skilled in the art to make and use my invention, I will proceed to describe its construction and operation.

The lever A, may be made of the same metal as the cylinder B, of the holder, or of other suitable material and the portion of it inserted in the said cylinder of the holder, is made narrower than the lower end. It is provided with pivots about midway between its ends, which pivots enter holes in the sides of the cylinder and serve as a fulcrum for it to move upon. It is provided with a pin C, at its upper end, passing through an opening in the cylinder from

the outside, and having a button or head on its end, situated in such relation to the fore finger of the hand of the penman, when grasping the holder to write, to enable him to depress the same at will, and is enlarged, or made the same width as the pen or nearly so, at the lower end, where it is provided with a small piece of sponge D, or other porous and elastic substance, which is either secured to its front surface, or simply confined between the same and the body of the pen, immediately above the nibs, in such a manner as to enable it to be readily taken out at any time to be cleansed, or for other purpose, and at the same time to have sufficient substance or bulk and elasticity to both retain the required quantity of ink, when dipped in the ink, to supply the nibs, and to force the lower portion of the lever from the pen, after it is pressed upon the sponge to extract the ink.

At each successive dipping of the pen in the ink, the penman inserts the nibs sufficiently far below the surface to enable the sponge to become sufficiently saturated with ink, as the occasion may require; and as it is used from the nibs of the pen, the button or head of the pen is pressed upon by the writer's forefinger, so as to depress the upper end of the lever, and compress the sponge between the lower widened part and the pen, and cause the ink absorbed in the same to flow upon the nibs to keep up the supply until the whole quantity is exhausted from the sponge, when it is again dipped and the operation repeated throughout the course of writing.

Having thus fully described my invention, what I claim as new and desire to secure by Letters Patent, is—

The combination of the sponge with the lever and pen, arranged and operated in the manner and for the purpose herein described.

WILLIAM H. TOWERS.
